UNITED STATES PATENT OFFICE

MONROE GUETT, OF HARTFORD, CONNECTICUT, ASSIGNOR TO THE ARROW-HART & HEGEMAN ELECTRIC COMPANY, OF HARTFORD, CONNECTICUT, A CORPORATION OF CONNECTICUT

ELECTRIC WIRING DEVICE

Application filed January 17, 1933. Serial No. 652,226.

This invention relates to electric wiring devices, more particularly it relates to means for interchangeably securing upon a supporting bridge or member a plurality of similar or dissimilar wiring devices of approximately the same size. Examples of the type of devices to which I refer are electric switches, electric attachment plug receptacles, and electric pilot or warning 10 light containers.

It is an object of this invention to make a bridge adapted to receive, interchangably, one or more electric wiring devices and to provide readily releasable means for securing said devices upon said bridge in such a manner that they may be readily secured in place, or removed upon the release of said securing means, without the use of tools.

Another object is to provide securing 20 means of the above type which are separable from the bridge or supporting member.

Another object is to provide one securing member which will suffice to hold one or more electric wiring devices upon a bridge 25 or support of the above type.

One advantage of this invention is that with a small number of different wiring devices in stock, many combinations of them mounted in various positions on a supporting bridge or any one of the devices mounted 30 alone on a bridge can be quickly assembled; or a previously assembled combination may be changed or completely disassembled quickly and without the use of any tools.

Other objects and advantages of my invention will become apparent as the invention is described in connection with the accompanying drawing:—

40 In the drawing:—

Figure 1 is a plan view of the invention.

Figure 2 is a left end view of Figure 1.

Figure 3 is a side elevation view of the invention shown in Figure 1 when mounted 45 in a wall box.

Figure 4 is a fragmentary plan view of a modified form of the invention.

Figure 5 is a sectional view, in end elevation of the modification shown in Figure 4, the section being taken on line 5—5 of Figure 4.

Referring to the drawing a bridge member 10 stamped from sheet metal has apertures 12 in its opposite ends through which screws may pass to secure the bridge in a single gang outlet or wall box 13. It is preferred to make the bridge short and narrow enough to fit into a single gang box, though it will be obvious that the size of the bridge and the other parts of this invention may be varied to suit the desires of the manufacturer or user of this device.

Preferably, low flanges 14 are bent up from the bridge on opposite sides and extending along the midportion of the bridge for about three fourths of its length, as illustrated in Figures 1 and 3 of the drawing.

The bridge 10 has one or more rectangular apertures 16 in its central portion for the reception of any of several types of wiring devices. In Figures 1 and 3 of the drawing, three apertures are shown in two of which are located an attachment plug receptacle 18 and a lever operated electric switch 20 respectively.

The switch mechanism and internal construction of these wiring devices form no part of this invention. Any one of a number of conventional single pole, double pole or three way switch mechanisms may be employed and it is not essential that it be operated by a lever. Likewise the construction of the attachment plug receptacle may be in any one of a number of conventional forms.

85 The casings in which the switch mechanism and parts of the attachment plug receptacle are contained are preferably rectangular, each casing being provided with a reduced neck 22 of dimensions slightly 90

smaller than the apertures 16 so as to be slidable therein. The casings of the switches and receptacles are made larger in cross-sectional area than the area of the apertures 16 thus forming shoulders 24 adjacent the necks 22. These shoulders rest against the lower or inner face of the bridge 10 and prevent the casings from passing through the apertures.

- 10 To hold the wiring devices in place upon the bridge a pair of parallel passages 25 are formed in the necks 22 just above the upper face of the bridge into which passages a securing member 26, hereinafter more fully described, slides. These passages run lengthwise of the bridge parallel to the flanges 14 and are so formed that the passages of one device (for example the switch 20) are in registry or alignment with the 20 passages of another device (for example attachment plug receptacle 18) when said devices are inserted in the apertures of the bridge.

The securing member 26 may be made 25 from wire or thin metal rod bent into U-shape with the transverse part 26a bent at right angles to the arms so as to be more readily grasped by a person's fingers during assembly of the wiring devices on the bridge 30 and their removal therefrom.

From the foregoing it will be readily understood that the devices 18 and 20 may have their necks slipped through the apertures 16 and held thereby sliding the securing device 26 through the parallel passages in the necks. The close proximity of the passages and securing member to the surface of the bridge prevents in-and-out movement of the wiring devices while the securing member is 40 in place.

In Figures 4 and 5, I have shown another method for securing the wiring devices on the bridge. In this form of the invention the bridge 40 is like bridge 20 except that 45 tongues 42 are formed on it and extend from one side into the bridge apertures. These tongues are adapted to fit into recesses or grooves 44 in the necks 43 of the wiring devices 45 on one side. In the other sides of 50 the necks are passages 46 similar to the passages 25 in Figures 1-3 for the securing device 26. Into these passages 46 a wire or thin rod 48 may be inserted. The securing rod 48 together with the tongue 42 will suffice to hold the wiring device on the bridge. Lateral and longitudinal movement of the devices in the apertures is prevented by the close fit of the necks in the apertures, and transverse or in-and-out movement is prevented by the shoulders 47 of the wiring devices engaging with one face of the bridge and by the engagement of the securing rod 48 with the other surface of the bridge and by the engagement of the tongue 42 with 65 both sides of the groove or recess 44.

Thus I have provided a very inexpensive means to secure wiring devices interchangeably on the bridge, and this means will not require any tools for its manipulation. My securing means is also advantageous because it does not require the removal of any other wiring devices which may be upon the bridge, if it is sought to remove a particular device. All that is necessary is to slide the securing member until the particular device is released. Any other devices that are incidentally released may be held in place, temporarily, by hand until the securing member is slid back in place.

I claim:

1. In combination, a one piece bridge member having a plurality of apertures therein and being adapted to be secured to the front of an outlet box, a plurality of independent wiring devices having portions adapted to fit into said apertures and being provided with passages which are in alignment when said necks are inserted in said apertures, and a detachable member independent of and slideable parallel with said bridge member and into said passages to secure said wiring devices detachably on said bridge member. 90
2. In combination, a one piece bridge member having a plurality of apertures therein and being adapted to be secured to the front of an outlet box, a plurality of independent wiring devices having portions adapted to fit into said apertures and being provided with parallel passages which are in alignment when said portions are inserted in said apertures, and a single U-shaped member slideable through all said passages to hold said devices on said bridge member. 100
3. In combination, a one piece bridge member having a plurality of apertures therein and being adapted to be secured to the front of an outlet box, a plurality of independent wiring devices having portions adapted to fit into said apertures and being provided with parallel passages which are in alignment when said portions are inserted in said apertures, and a single U-shaped member slideable through all said passages to hold said devices on said bridge member, said securing member being located on the opposite side of said bridge from the main bodies of said wiring devices. 110

4. In combination, a one piece bridge member having apertures therein and being adapted to be secured to the front of an outlet box, a plurality of electric wiring devices having casings with portions adapted to fit within said apertures and a single detachable member independent of said bridge member to detachably secure all said wiring devices on said bridge member. 120

5. In combination, a one piece bridge member having a plurality of apertures therein and being adapted to be secured to

the front of an outlet box, a plurality of independent wiring devices having portions adapted to fit into said apertures and being provided with passages which are in alignment when said necks are inserted in said apertures, and a detachable member independent of said bridge member and slidable into said passages to secure said wiring devices detachably on said bridge member.

10 In testimony whereof I have signed my name to this specification.

MONROE GUETT.
